(57) **CLAIM**

The ornamental design for a seat back device holding apparatus, as shown.

DESCRIPTION

FIG. 1 is a perspective view of a seat back device holding apparatus showing my new design;

FIG. 2 is a front view thereof;

FIG. 3 is a back view thereof;

FIG. 4 is a side view thereof;

FIG. 5 is a top view thereof;

FIG. 6 is a bottom view thereof;

FIG. 7 is another perspective view thereof; and,

FIG. 8 is another side view thereof.

The broken lines illustrate portions of the seat back device holding apparatus or environmental structure that do not form a part of the claimed design.
